No. 882,424.

PATENTED MAR. 17, 1908.

W. SCHARHAUSEN.
INSULATOR PIN.
APPLICATION FILED JUNE 10, 1907.

UNITED STATES PATENT OFFICE.

WILLIAM SCHARFHAUSEN, OF PAYETTE, IDAHO, ASSIGNOR TO PAYETTE INSULATOR PIN COMPANY, LIMITED, OF PAYETTE, IDAHO.

INSULATOR-PIN.

No. 882,424.

Specification of Letters Patent. Patented March 17, 1908.

Application filed June 10, 1907. Serial No. 378,178.

To all whom it may concern:

Be it known that I, WILLIAM SCHARFHAUSEN, residing at Payette, in the county of Canyon and State of Idaho, have invented 5 certain new and useful Improvements in Insulator - Pins, of which the following is a specification.

My invention relates to certain new and useful improvements in insulator pins and it 10 particularly seeks to provide an improved means of securing the pin into the cross arm as well as to provide an improved construction of pin which will be of maximum strength with minimum amount of materials used in its construction.

My invention also embodies certain novel details of construction, combination and arrangement of parts, all of which will be first described in detail, and then specifically 20 pointed out in the appended claims, reference being had to the accompanying drawings, in which:

Figure 1, is a perspective view of the end 25 of a cross arm with my improved invention applied. Fig. 2, is a side elevation of the insulator pin and cross arm, the cross arm being shown in section. Fig. 3, is a vertical longitudinal section of the invention showing the position of the parts when the securing nail or spike is being driven in. Fig. 4, 30 is a section on the line 4—4 of Fig. 3, the parts being in the position in which the nail or spike has been driven home and the first 35 clench or bend of the nail having been made. Fig. 5, is a horizontal section on the line 5—5 of Fig. 4. Fig. 6, is a similar view after the spike or nail has been clenched to its final position.

Referring now to the accompanying drawings, in which like numerals and letters of 40 reference indicate like parts in all of the figures, it will be seen that 1 designates the insulator pin which is provided with the cross arm engaging portion 1^a and the insulator carrying portion 1^b, which is provided with a thread 1^c to receive the insulator, or the thread 1^c may be omitted, if desired.

1^d designates a slot which extends to the upper edge of the body portion 1^a and at its 50 lower end the slot 1^d has a beveled portion 1^e which merges with the outer face of the body portion 1^a.

At right angles to the slot 1^e, the insulator carrying portion 1^b of the pin is provided

with a horizontal slot 1^f for a purpose which 55 will be presently explained.

2 designates the cross arm in the apertures 2^a of which the body portion 1^a of the pin is adapted to be held and the manner in which the pin is held in the cross arm will 60 now be explained.

3 designates a nail or spike of any approved type, such for instance as the wire nail type, which after the nail has been placed in the cross arm aperture, is driven in 65 through the slot 1^d and as soon as the point 3^a of the nail or spike 3 engages the beveled portion 1^e of the slot it will be driven into the cross arm and after the nail has been driven in the desired amount, the upper portion 70 is bent over as at 3^b at substantially right angles to the portion lying in the slot 1^d, and is then again bent at substantially right angles to itself as at 3^c to lie in the slot 1^f. 75

Thus it will be seen that my improved insulator pin and means for securing the same is of a very simple and effective construction and can be easily and cheaply constructed, and the spike or nail 3 is locked in position to 80 prevent any accidental withdrawal of the same, and furthermore the lower end of the spike is driven at an acute angle to the axial line of the pin, and hence serves as a locking wedge to maintain the pin in the cross arm 85 aperture.

From the foregoing description taken in connection with the accompanying drawings it is thought the complete construction, 90 operation and many advantages of my invention will be readily understood by those skilled in the art to which the invention appertains, and it may be further understood that any approved type of insulator 4 may be used in connection with the pin 1 since the 95 particular construction of the insulator 4 forms no part of my present invention.

What I claim is:

1. An insulator pin comprising a base portion and an insulator carrying portion 100 said base portion having a longitudinal slot, and said insulator carrying portion having a transverse slot, said longitudinal slot at one end terminating adjacent said transverse slot, substantially as shown and described. 105

2. An insulator pin comprising a base portion and a reduced insulator carrying portion, said base portion having a longitu-

dinal slot terminating at its lower end in an outwardly beveled portion, and said insulator carrying portion having a transverse slot held at substantially right angles to the 5 longitudinal slot, all being arranged substantially as shown and described.

3. The combination with an insulator pin having a base portion and a cross arm having an aperture to receive such base portion, said 10 insulator pin having an insulator carrying portion projecting upwardly from the base portion, said base portion having a longitudinal slot, of a locking member held in said longitudinal slot and projected into said 15 cross arm, and means carried by the insulator carrying portion of the pin for coöperatively engaging with the locking member to lock the locking member in place, substantially as shown and described.
- 20 4. The combination with an insulator pin having a base portion and a cross arm having an aperture to receive such base portion, said insulator pin having an insulator carrying portion projecting upwardly from the base 25 portion, said base portion having a longitudinal slot, of a locking member held in said

longitudinal slot and projected into said cross arm, means carried by the insulator carrying portion of the pin for coöperatively engaging with the locking member to lock 30 the locking member in place, said last named means consisting of a groove in the insulator carrying portion of the pin to receive an up-set or bent-over portion of the locking means, substantially as shown and described.

35 5. An insulator pin comprising a base portion and an insulator carrying portion, said base portion having a longitudinal slot in its outer wall, combined with a cross arm or support having an aperture to receive said 40 base portion, a locking member held in said longitudinal slot and projected into the cross arm and having its upper end bent around said insulator carrying portion of the pin to lie in a plane substantially at right angles to 45 that containing the longitudinal slot, substantially as shown and described.

WILLIAM SCHARFHAUSEN.
